UNITED STATES PATENT OFFICE.

CLARENCE H. MARTIN, OF ENDEAVOR, WISCONSIN.

LIGHTNING-ARRESTER.

1,271,050.

Specification of Letters Patent.

Patented July 2, 1918.

Application filed May 23, 1917. Serial No. 170,488.

To all whom it may concern:

Be it known that I, CLARENCE H. MARTIN, a citizen of the United States, residing at Endeavor, in the county of Marquette and 5 State of Wisconsin, have invented certain new and useful Improvements in Lightning-Arresters, of which the following is a specification.

This invention relates to lightning arresters and more particularly to the type in which a magnet by attracting an armature produces a ground connection, so as to direct the flow of lightning or any undesirable charge of electricity to the earth. 10 15 The main object of the invention is to provide a simple and efficient device of this character, especially designed for protecting telephones and which is so constructed as to automatically direct and conduct an excessive flow of current to the earth and when this is effected, to immediately and automatically return to its normal condition ready for the next discharge.

With the foregoing and other objects in view, which will appear as the description proceeds, the invention resides in the combination and arrangement of parts and in the details of construction herein after described and claimed, it being understood that 20 changes in the precise embodiment of the invention herein disclosed may be made within the scope of what is claimed without departing from the spirit of the invention.

In the accompanying drawings:—

25 Fig. 1 represents a front elevation of an arrester constructed in accordance with this invention,

Fig. 2 is a similar view with parts broken out and in section, and

Fig. 3 is a side elevation thereof.

In the embodiment illustrated, the arrester constituting this invention comprises a suitable base 1 of hard rubber or other suitable non-conducting material on which is mounted 45 an electrode in the form of a block 2 of carbon or other suitable material with which is connected a ground wire 3 by the usual binding post 4.

Two carbon block electrodes 5 and 6 are 50 secured to the base 1 at points spaced from the block 2 and from each other as is shown clearly in Figs. 1 and 2. As shown, the combined length of these blocks 5 and 6 with the space between them corresponds to the 55 length of block 2 and the outer ends of said

blocks 5 and 6 are arranged in alinement with the ends of block 2 for a purpose to be described.

A hollow spool 7 is also mounted on base 1 and is composed of rubber or other suitable insulating material, and has an annular flange 8 arranged midway the ends thereof to divide the spool into two sections, on each of which is coiled a wire. A wire 9 is coiled around the left hand end of the spool and has one terminal thereof secured to the carbon block 5 by an ordinary binding post 10, the other end of this wire 9 leads to the telephone to be protected. Another wire 11 is wound around the other portion of the spool 7 between the flange 8 and the outer flange 8' at the right hand side of the spool. One terminal of this wire 11 is connected with the carbon block 6 by a binding post 10' in a manner similar to the wire 9. The other 75 end of the wire 11 leads to the telephone, (not shown).

Two brackets as 12 project laterally from the base 1 at the end opposite that which carries block 2. These brackets 12 are arranged in transverse alinement and support flat metal strips 13 which are secured at one end to said brackets and are provided at their free ends with electrodes in the form of carbon blocks as 14, which are positioned opposite the ends of block 2 and the outer ends of blocks 5 and 6 and are normally spaced therefrom.

Metal cores as 15 are carried by the spring strips 13 intermediately the ends thereof and are disposed within the spool 7 as is shown clearly in Fig. 2, said cores being adjustably connected with said springs by means of set screws as 16 to provide for the proper adjustment of the cores relatively to the 95 springs to enable the device to operate in the manner hereinafter set forth.

By so winding the wires 9 and 11 around the spool 7, said spool is designed to operate as a magnet when an excessive current passes 100 through either wire and hence attracts the core 15 at the end of the spool around which the magnetized wire is wrapped and draws said core into the spool thereby causing block 14 to engage the opposed ends of the block 2 and of the block 5 or 6, and thus close the circuit and permit the current to pass out through block 2 and wire 3 to the ground. When the other wire receives an excessive charge of current, it will operate in the same 110

manner and close the armature at that side of the device, permitting an excessive flow of current to pass out through block 2 and wire 3 to the ground.

5 In the use of this device, the armatures 14 having been adjusted to that degree of sensitiveness that the line currents are normally insufficient to close the ground connections and which is the position shown in Figs. 1 10 and 2, should a lightning charge strike either of the line wires 9 or 11 or any atmospheric electrical disturbance cause an increase of potential, in the line, the tension of the spring 13 enables the armature 14 to move 15 laterally inward and thereby close the ground circuit allowing the superfluous current to escape. After the static discharge is effected, the arrester immediately and automatically assumes or returns to its normal 20 state so as to be in condition for successively discharging any number of excessive charges or currents imposing themselves thereon without injuring or impairing the operativeness of the arrester and without 25 necessitating manual adjustment of the arrester or any of its parts.

From the foregoing description, taken in connection with the accompanying drawings, the advantages of the construction and 30 of the method of operation will be readily apparent to those skilled in the art to which the invention appertains and while I have described the principle of operation of the invention together with the device which I 35 now consider to be the best embodiment thereof, I desire to have it understood that the device shown is merely illustrative and that such changes may be made as are within the scope of the claimed invention.

40 I claim:—

1. A lightning arrester comprising a base, an electrode mounted thereon, a ground wire connected with said electrode, a pair of electrodes mounted on said base and spaced 45 from said first mentioned electrode and from each other with their outer ends in alinement with the ends of said first mentioned electrode, a hollow hard rubber spool having a flange extending radially therefrom intermediate of its ends, a pair of wires coiled on said spool one on each side of said flange, one end of each wire being connected with 50 one of said pair of electrodes, cores mounted in the ends of said spool, plate springs secured at one end to said support and having electrodes at their other ends positioned to engage said above mentioned electrodes, on the inward movement of the springs, said

springs being connected intermediately of their ends with said cores. 60

2. A lightning arrester comprising a base, an electrode mounted thereon, a ground wire connected with said electrode, a pair of electrodes mounted on said base and spaced from said first mentioned electrode and from each other with their outer ends in alinement with the ends of said first mentioned electrode, a hollow hard rubber spool having a flange extending radially therefrom intermediate of its ends, a pair of wires coiled 70 on said spool one on each side of said flange, one end of each wire being connected with one of said pair of electrodes, cores mounted in the ends of said spool, plate springs secured at one end to said support and having 75 electrodes at their other ends positioned to engage said above mentioned electrodes, on the inward movement of the springs, said springs being connected intermediately of their ends with said cores, and means for 80 varying the connection between said springs and cores.

3. In an arrester of the class described, a base of non-conducting material, an electrode mounted thereon, a ground wire connected with said electrode, a pair of electrodes secured to said base at points spaced from said first mentioned electrode and from each other, the outer ends of said pair of electrodes being in alinement with the ends of said first mentioned electrode, a spool of insulating material also mounted on said base and having an annular radially extending flange intermediate its ends to divide the spool into sections, a wire coiled on each section and secured to one of said pair of electrodes at one end and with its other end adapted to be secured to the object to be protected, flat metal strips secured at one end to said base, electrodes carried by the free 100 ends of said strips and positioned opposite the alined ends of said first mentioned electrodes and normally spaced therefrom, and metal cores carried by said strips and disposed within said spool and adapted to be 105 attracted and moved into the spool to close the ground circuit when an excessive current passes through either wire wound on the spool.

In testimony whereof I affix my signature 110 in presence of two witnesses.

CLARENCE H. MARTIN.
